CLAIM

I claim the ornamental design for a utility cart, as shown and described.

DESCRIPTION

FIG. 1 is a side, top perspective view of the utility cart of the present invention.

FIG. 2 is a front view thereof;

FIG. 3 is a rear view thereof;

FIG. 4 is a right-side view thereof;

FIG. 5 is a left-side view thereof;

FIG. 6 is a top view thereof; and,

FIG. 7 is a bottom view thereof.

In the drawings, the broken lines show portions of the utility cart that form no part of the claimed design.
